(57) **ABSTRACT**

A fire-rated component for a linear gap between a wall assembly and an adjacent structure. The component includes an elongate metal profile and a fire-rated board member. The elongate metal profile has a vertical leg, an upper leg and a lower leg. The upper leg extends in a first direction from an upper edge of the vertical leg. The lower leg extends in the first direction from a lower edge of the vertical leg. The fire-rated board member is positioned within a space defined by the vertical leg, the upper leg and the lower leg.

FIRE-RATED WALL JOINT COMPONENT
AND RELATED ASSEMBLIES

CROSS-REFERENCE

This application claims the benefit of U.S. Application No. 62/942,423 filed on Dec. 2, 2019, the entirety of which is hereby incorporated by reference.

BACKGROUND

Field

This application is directed to fire-rated wall construction components for use in building construction joints.

Related Art

Fire-rated wall construction components and assemblies are commonly used in the building construction industry. These components and assemblies are aimed at preventing fire, heat, and smoke from leaving one portion of a building or room and entering another, usually through vents, joints in walls, or other openings. The components can incorporate fire-retardant materials which substantially block the path of the fire, heat, and/or smoke for at least some period of time in accordance with certain standards, such as UL-2079 "Test For Fire-rated Building Joints".

Conventional fire-rated wall construction components are typically labor intensive and expensive to install. One example of a conventional fire block arrangement includes using a fire-resistant material such as mineral wool stuffed in the gaps within a head-of-wall assembly including deflection gaps between the top of the wall boards and the ceiling. Once the gaps are filled with the fire block material, a flexible coating such as a spray-on elastomeric coating can cover the entire head-of-wall to secure the fire block material in place. Over time and cycles of movement the flexible coating may degrade and cause cracks or flaking. As a result, it is possible that the fire-resistant material may become dislodged and thereby reduce the effectiveness of the fire block.

SUMMARY

One aspect of the present disclosure is a fire-rated component for a linear gap between a wall assembly and an adjacent structure. The component includes an elongate metal profile and a fire-rated board member. The elongate metal profile includes a vertical leg, an upper leg and a lower leg. The upper leg extends in a first direction from an upper edge of the vertical leg. The lower leg extends in the first direction from a lower edge of the vertical leg. The fire-rated board member is positioned within a space defined by the vertical leg, the upper leg and the lower leg to form a composite component.

According to another aspect, the upper leg includes a downward facing v-groove. According to another aspect, the upper leg includes an extended free end attachment leg. According to another aspect, an outward facing protrusion on the vertical leg rests against the drywall board of the framed wall assembly with the outward facing protrusion extending in a second direction, opposite the first direction. According to another aspect, the gypsum board member is adhesively attached with the vertical leg. According to another aspect, the lower leg includes a kick-out configured to retain a gypsum board member within the space. Accord-

2

ing to another aspect, the upper leg, the lower leg, the v-groove, and the kick-out are configured to exert a force against the gypsum board member to retain the gypsum board in the space. According to another aspect, the lower leg determines the thickness of the layer or layers of the gypsum board member. According to another aspect, the metal profile is formed from a unitary piece of sheet steel and bent to form the vertical leg. According to another aspect, the board member comprises a gypsum material.

10 In another aspect of the present disclosure, a building construction joint includes a wall assembly and an adjacent structure formed along a linear gap. A fire-rated component including an elongate metal profile and a fire-rated board member is positioned at a joint between the wall assembly and the adjacent structure to provide fire-blocking across the linear gap. According to another aspect, the adjacent structure is a ceiling and the wall assembly is a vertical wall.

15 The foregoing summaries are illustrative only and are not intended to be limiting. Other aspects, features, and advantages of the systems' devices and methods and/or other subject matter described in this application will become apparent in the teaching set forth below. The summaries provided introduce a selection of some of the concepts of this disclosure. The summary is not intended to identify key or essential features of any subject matter described herein.

BRIEF DESCRIPTION OF THE DRAWINGS

20 Various examples are depicted in the accompanying drawings for illustrative purposes and should in no way be interpreted as limiting the scope of the examples. Various features of different disclosed examples can be combined to form additional examples which are part of this disclosure.

25 FIG. 1 illustrates a cross section of a head-of-wall assembly including a composite fire-blocking component.

30 FIG. 2A shows a cross-section of the head-of-wall assembly in a fully closed configuration.

35 FIG. 2B shows a cross-section of the head-of-wall assembly in a fully opened configuration.

40 FIG. 3 shows a cross-section of the composite fire-blocking component including a metal profile and board member.

45 FIG. 4 shows a cross-section of an elongate metal profile.

DETAILED DESCRIPTION

FIGS. 1-2B illustrate a building construction joint between a wall assembly and an adjacent structure having a linear gap in the form of a head-of-wall assembly 100. The embodiments disclosed herein often are described in the context of an interior of a building and configured for preventing passage of smoke and/or fire between adjacent rooms in an elevated-temperature environment. However, the embodiments herein can be applied to wall systems configured for other types of environments as well, such as for exterior wall applications, and can include different and/or additional components and types of materials other than those described herein.

50 The head-of-wall assembly 100 can generally include an overhead structure or ceiling 105. The ceiling 105 can be generally formed in a horizontal plane and/or include one or more flutes or grooves therein. The ceiling 105 can be a floor of a higher level of a building. The head-of-wall assembly 100 can include a header track or channel 107. The channel 107 can include a web 107a to which are attached one or more flanges 107b, 107c. The first and second flanges 107b, 107c can extend from opposite ends of the web 107a in the

same direction to form a generally u-shaped cross section. Optionally, the channel 107 can be a deep leg header track.

One or more studs 109 forming the wall can be received within the channel 107 between the first and second flanges 107b, 107c. The first and second flanges 107b, 107c can include slots to which fasteners can be received to attach the channel 107 with the studs 109. The slots can be oriented generally orthogonal to a length of the channel 107. The studs 109 can be attached with the channel 107 via fasteners through the slots of the flanges 107b, 107c.

One or more wall board members (e.g., gypsum drywall) 111, 113 can be attached with the studs 109 to form the wall. Assembly of the wall boards 111, 113 with the studs 109 can define a deflection gap 101 between the ceiling 105 and upper ends of the wall boards 111, 113. The deflection gap 101 can vary in width depending on the relative position of the wall (e.g., wall boards 111, 113 and the studs 109) and the ceiling 105. The head-of-wall assembly 100 can cycle between a more closed position (such as the fully closed position in FIG. 2A) and a more open position (such as the fully open position in FIG. 2B). The dynamic nature of the head-of-wall assembly 100 can accommodate seismic or thermal forces or other movements of the building within which the head-of-wall assembly 100 is included.

The head-of-wall assembly 100 can include a fire-rated composite component 10. The composite component 10 can generally be configured to cover the deflection gap 101 to provide fire, smoke, heat and/or sound insulation and facilitate unencumbered movement of the joint. The component 10 can include an elongate metal profile 12 and a board member 14. The board member 14 can comprise a fire-rated material, such as a gypsum drywall material. In certain implementations, the board member 14 can adhesively attached or otherwise mechanically secured with the metal profile 12 to form the composite component 10.

The composite component 10 can be installed over the outer surface of the wall boards 111, 113 and/or the flanges 107b, 107c on the framed wall assembly once the drywall assembly is completed. The component 10 can be attached with the ceiling 105 by one or more fasteners 103, such as metal screws, adhesives, staples or other fasteners. The fasteners 103 can extend through the metal profile 12. The fire board member 14 can insulate the metal profile 12, while the metal profile 12 provides a constant fire block as it will not melt during the fire test of UL 2079. The combination of these two materials provides long lasting fire protection. In addition, drywall used in the board member 14 is less expensive than other fire-resistant materials, such as intumescent materials, that are often used in head-of-wall assemblies or other gaps of a building construction joint.

The metal profile 12 can come in standard lengths (e.g., 10', 12', etc.). As shown further in the cross-section of FIG. 3, the metal profile 12 can include a single sheet of metal, such as steel. The metal profile 12 can include a plurality of bends to form the metal profile shape. The metal profile 12 can include, a vertical leg 16, an upper leg 24, and/or a lower leg 20. The vertical leg 16 can have a length L extending from the upper leg 24 to the lower leg 20. The length L can vary depending on the size of the head-of-wall deflection gap 101 and the overall dynamic movement needed. The length L can generally be between about 1" and 6". The vertical leg 16 can comprise a flattened portion of the metal profile 12. Alternatively, the vertical leg 16 can comprise one or more strengthening features such as grooves or ribs.

The upper leg 24 can couple with the vertical leg 16 at a corner 34. The upper leg 24 can generally form perpendicular angle with the vertical leg 16. The upper leg 24 can

extend from the corner 34 in a first (e.g., rightward) direction. The upper leg 24 can be a horizontal leg. The upper leg 24 can be approximately 1.5"-3.5" in length.

The upper leg 24 can include a groove 22. The groove 22 can be shaped as a v-groove, u-groove, or other form factor. The groove 22 can include an open end facing upwards and outwards. The groove 22 can provide structural strength to the metal profile 12 and to the upper leg 24. Other retention features and/or strengthening features could also be used.

10 The groove 22 can extend downwardly towards the lower leg 20. The groove 22 can divide the upper leg into an inner portion 25 and an outer portion 26. The inner portion 25 can be in-line with the outer portion 26. The inner portion 25 can have a width W1 from the corner to the groove 22 (e.g., approximately 0.625"). The outer portion 26 can include an attachment portion of the metal profile 12. The outer portion 26 can have a width of approximately 1.25". The attachment can include one or more holes or other mechanism to allow an installer to attach the metal profile 12 to the ceiling 105 (or other adjoining structure).

15 The lower leg 20 can couple with the vertical leg 16 at a corner 30. The lower leg 20 can generally form perpendicular angle with the vertical leg 16. The lower leg 20 can extend from the corner 30 in the first (e.g., rightward) direction. The lower leg 20 can extend in the same direction as the upper leg 24. The lower leg 20 can be a horizontal leg.

20 The lower leg 20 can include a kick-out 32. The kickout 32 can be on a free end of the lower leg 20. The kickout 32 can include an upturned retention lip or portion of the lower leg 20 (e.g., towards the upper leg 24). The kick-out 32 can be angled upwardly towards the upper leg 24. The lower leg 20 can include a width W2 from the corner 30 to the free end or the kickout 32. The width W2 can optionally be the same as the width W1.

25 The lower leg 20, the vertical leg 16, and the upper leg 24 can form an inner, partially enclosed space. The inner space can receive and secure the board member 14. The board member 14 can comprise a fire-rated drywall member. The board member 14 can comprise one or more layers of material. The board member 14 can be a rip of drywall comprising a gypsum material. The board member 14 can include a generally rectangular-shaped profile. The board member 14 can nest within the inner space between the upper leg 24, the vertical leg 16, and the lower leg 20. Preferably, the width W1 of the upper leg 24 and the width W2 of the lower leg 20 can be sized to accommodate a width W3 of the board member 14. The kickout 32 and/or the groove 22 can exert an inward force on the board member 14 to help retain the board member 14 within the inner space and/or against the vertical leg 16. In certain implementations, the width W1 can be the same as width W2 and correspond to the width W3 of the board member 14. The widths W1, W2 can limit the W3 of the board member 14 that can be used in the composite component 10.

30 An interior side of the board member 14 can be glued to the vertical leg 16 with an adhesive or secured with a mechanical fastener. The adhesive can secure the board member 14 within the inner space of the metal profile 12. The kickout 32 and/or groove 22 can also retain the board member in place within the metal profile and ensure it will not fall out during a fire that may compromise the adhesive. The groove 22 and/or kickout 32 can be shaped in any suitable shape for retention of the board member 14 and/or strengthening of the composite 10.

35 The corner 30 can include an inward facing protrusion (e.g., towards the wall boards 111, 113) that sticks out further than the interior surface of the vertical leg 16 (e.g., approxi-

mately 0.125"). The inward facing protrusion can be formed of a bend in the metal of the metal profile 12. In the installed position with the head-of-wall assembly 100, the protrusion can provide a sealing point against one of the board members 111, 113 of the framed wall assembly. This protrusion can also allow the wall to cycle up and down, as is needed in order to pass the UL-2079 "Test For Fire-rated Building Joints" without causing any damage to the drywall on the framed wall assembly. In other configurations, one or both of the protrusion of the corner 30 and kickout 32 can be omitted.

In the installed configuration within the head-of-wall assembly 100, the board member 14 can be nested within the inner space of the metal profile 12. The upper leg 24 can abut against and attached with the ceiling 105 (e.g., by fastener 103). The vertical leg 16 can abut an upper end of the wall board 113 and cover the deflection gap 101. The protrusion of the corner 30 can abut the outer face of the wall board 113 to provide a seal therewith. The wall board 113 can cycle behind the installed composite component 10 between open and closed configurations.

FIG. 4 illustrates an alternative metal profile 12a. The metal profile 12a can include a vertical leg 16, an upper leg 24, and a lower leg 20, like the metal profile 12 previously described. An upward facing protrusion 34a can be formed of a bent portion of the material of the metal profile 12a on the upper leg 24 (e.g., approximately 0.125"). The upward facing protrusion can be directed or extend generally upwardly. In the installed configuration, the protrusion can contact and provide a sealing point against the ceiling 105 of the assembly 100. In the installed configuration within the head-of-wall assembly 100, the upper leg 24 can abut against and attached with the ceiling 105. The upward facing protrusion of the corner 30 can abut the ceiling 105 to provide a seal therewith. The wall board 113 can cycle behind the installed composite component 10 between open and closed configurations.

Certain Terminology

Terms of orientation used herein, such as "top," "bottom," "proximal," "distal," "longitudinal," "lateral," and "end," are used in the context of the illustrated example. However, the present disclosure should not be limited to the illustrated orientation. Indeed, other orientations are possible and are within the scope of this disclosure. Terms relating to circular shapes as used herein, such as diameter or radius, should be understood not to require perfect circular structures, but rather should be applied to any suitable structure with a cross-sectional region that can be measured from side-to-side. Terms relating to shapes generally, such as "circular," "cylindrical," "semi-circular," or "semi-cylindrical" or any related or similar terms, are not required to conform strictly to the mathematical definitions of circles or cylinders or other structures, but can encompass structures that are reasonably close approximations.

Conditional language, such as "can," "could," "might," or "may," unless specifically stated otherwise, or otherwise understood within the context as used, is generally intended to convey that certain examples include or do not include, certain features, elements, and/or steps. Thus, such conditional language is not generally intended to imply that features, elements, and/or steps are in any way required for one or more examples.

Conjunctive language, such as the phrase "at least one of X, Y, and Z," unless specifically stated otherwise, is otherwise understood with the context as used in general to

convey that an item, term, etc. may be either X, Y, or Z. Thus, such conjunctive language is not generally intended to imply that certain examples require the presence of at least one of X, at least one of Y, and at least one of Z.

5 The terms "approximately," "about," and "substantially" as used herein represent an amount close to the stated amount that still performs a desired function or achieves a desired result. For example, in some examples, as the context may dictate, the terms "approximately," "about," and "substantially," may refer to an amount that is within less than or equal to 10% of the stated amount. The term "generally" as used herein represents a value, amount, or characteristic that predominantly includes or tends toward a particular value, amount, or characteristic. As an example, in 10 certain examples, as the context may dictate, the term "generally parallel" can refer to something that departs from exactly parallel by less than or equal to 20 degrees. All 15 ranges are inclusive of endpoints.

20

SUMMARY

Several illustrative examples of construction joints have been disclosed. Although this disclosure has been described in terms of certain illustrative examples and uses, other 25 examples and other uses, including examples and uses which do not provide all of the features and advantages set forth herein, are also within the scope of this disclosure. Components, elements, features, acts, or steps can be arranged or performed differently than described and components, elements, features, acts, or steps can be combined, merged, added, or left out in various examples. All possible 30 combinations and subcombinations of elements and components described herein are intended to be included in this disclosure. No single feature or group of features is necessary or indispensable.

Certain features that are described in this disclosure in the context of separate implementations can also be implemented in combination in a single implementation. Conversely, various features that are described in the context of 35 40 a single implementation also can be implemented in multiple implementations separately or in any suitable subcombination. Moreover, although features may be described above as acting in certain combinations, one or more features from a claimed combination can in some cases be excised from the 45 combination, and the combination may be claimed as a subcombination or variation of a subcombination.

Any portion of any of the steps, processes, structures, and/or devices disclosed or illustrated in one example in this disclosure can be combined or used with (or instead of) any 50 other portion of any of the steps, processes, structures, and/or devices disclosed or illustrated in a different example or flowchart. The examples described herein are not intended to be discrete and separate from each other. Combinations, variations, and some implementations of the disclosed features are within the scope of this disclosure.

While operations may be depicted in the drawings or described in the specification in a particular order, such operations need not be performed in the particular order shown or in sequential order, or that all operations be 55 performed, to achieve desirable results. Other operations that are not depicted or described can be incorporated in the example methods and processes. For example, one or more additional operations can be performed before, after, simultaneously, or between any of the described operations. Additionally, the operations may be rearranged or reordered in some implementations. Also, the separation of various components in the implementations described above should

not be understood as requiring such separation in all implementations, and it should be understood that the described components and systems can generally be integrated together in a single product or packaged into multiple products. Additionally, some implementations are within the scope of this disclosure.

Further, while illustrative examples have been described, any examples having equivalent elements, modifications, omissions, and/or combinations are also within the scope of this disclosure. Moreover, although certain aspects, advantages, and novel features are described herein, not necessarily all such advantages may be achieved in accordance with any particular example. For example, some examples within the scope of this disclosure achieve one advantage, or a group of advantages, as taught herein without necessarily achieving other advantages taught or suggested herein. Further, some examples may achieve different advantages than those taught or suggested herein.

Some examples have been described in connection with the accompanying drawings. The figures are drawn and/or shown to scale, but such scale should not be limiting, since dimensions and proportions other than what are shown are contemplated and are within the scope of the disclosed invention. Distances, angles, etc. are merely illustrative and do not necessarily bear an exact relationship to actual dimensions and layout of the devices illustrated. Components can be added, removed, and/or rearranged. Further, the disclosure herein of any particular feature, aspect, method, property, characteristic, quality, attribute, element, or the like in connection with various examples can be used in all other examples set forth herein. Additionally, any methods described herein may be practiced using any device suitable for performing the recited steps.

For purposes of summarizing the disclosure, certain aspects, advantages and features of the inventions have been described herein. Not all, or any such advantages are necessarily achieved in accordance with any particular example of the inventions disclosed herein. No aspects of this disclosure are essential or indispensable. In many examples, the devices, systems, and methods may be configured differently than illustrated in the figures or description herein. For example, various functionalities provided by the illustrated modules can be combined, rearranged, added, or deleted. In some implementations, additional or different processors or modules may perform some or all of the functionalities described with reference to the examples described and illustrated in the figures. Many implementation variations are possible. Any of the features, structures, steps, or processes disclosed in this specification can be included in any example.

In summary, various examples of construction joints and related methods have been disclosed. This disclosure extends beyond the specifically disclosed examples to other alternative examples and/or other uses of the examples, as well as to certain modifications and equivalents thereof. Moreover, this disclosure expressly contemplates that various features and aspects of the disclosed examples can be combined with, or substituted for, one another. Accordingly, the scope of this disclosure should not be limited by the particular disclosed examples described above, but should be determined only by a fair reading of the claims.

The invention claimed is:

1. A fire-rated component for a linear gap between a wall assembly and an adjacent structure, the component comprising:

an elongate metal profile comprising a vertical leg, an upper leg and a lower leg, the upper leg extending in a

first direction from an upper edge of the vertical leg, the lower leg extending in the first direction from a lower edge of the vertical leg, wherein the upper leg and the lower leg are configured to be oriented to extend in a direction away from a header track in use;

a fire-rated board member nested between the upper leg and the lower leg;

wherein an upper end of the fire-rated board member is positioned below the upper leg and a lower end of the fire-rated board member is positioned above the lower leg;

wherein the upper leg comprises a first portion connected to the vertical leg, the first portion having a first edge and defining a plane, a second portion having a second edge positioned within the plane, and a downward extending protrusion connecting the first portion to the second portion, wherein the downward extending protrusion is connected to the first portion along the first edge and to the second portion along the second edge.

2. The component of claim 1, further comprising an outward facing protrusion on the vertical leg configured to rest against a drywall board of the wall assembly, the outward facing protrusion extending in a second direction, opposite the first direction.

3. The component of claim 1, wherein the board member is adhesively attached to the vertical leg.

4. The component of claim 1, wherein the lower leg comprises a kickout configured to retain the board member within the elongate metal profile.

5. The component of claim 4, wherein any one or combination of the upper leg, the lower leg, the downward extending protrusion and the kickout are configured to exert a force against the board member to retain the board member within the elongate metal profile.

6. The component of claim 1, wherein a width of the board member is limited by a width of the lower leg.

7. The component of claim 1, wherein the metal profile comprises a single sheet of bent steel.

8. The component of claim 1, wherein the board member comprises a gypsum material.

9. A building construction joint, comprising:
the wall assembly and the adjacent structure with the linear gap extending therebetween; and the component of claim 1 positioned between the wall assembly and the adjacent structure to provide fire-blocking across the linear gap.

10. The building construction joint of claim 9, wherein the adjacent structure is a ceiling.

11. The component of claim 1, further comprising an upward facing protrusion on the upper leg configured to abut the adjacent structure.

12. The component of claim 1, wherein the downward extending protrusion comprises a V-groove.

13. A fire-rated component for a linear gap between a wall assembly and an adjacent structure, the component comprising:

an elongate metal profile comprising:

a vertical leg;
an upper leg comprising a first portion connected to the vertical leg, the first portion having a first edge and defining a plane, a second portion having a second edge positioned within the plane, a groove connecting the first portion to the second portion, wherein the groove is connected to the first portion along the first edge and to the second portion along the second edge; and a lower leg;

wherein the upper leg extends in a first direction from an upper edge of the vertical leg, the lower leg extends in the first direction from a lower edge of the vertical leg, and the groove extends in a second direction from the upper leg, the second direction extending towards the lower leg from the upper leg;

5 a fire-rated board member nested within a space defined by the elongate metal profile with an upper end of the fire-rated board member positioned between the vertical leg and the groove of the upper leg.

14. The fire-rated component of claim 13, wherein the groove of the upper leg comprises a V-shaped groove between the second portion and the vertical leg.

15. The fire-rated component of claim 13, wherein any one or combination of the upper leg, the lower leg, and the groove of the upper leg exert a force against the board member to retain the board member nested within the elongate metal profile.

16. A fire-rated component for a linear gap between a wall assembly and an adjacent structure, the component comprising:

an elongate metal profile comprising a vertical leg, an upper leg and a lower leg, the upper leg extending in a first direction from an upper edge of the vertical leg, the lower leg extending in the first direction from a lower edge of the vertical leg, and the upper leg spaced from the lower leg by a first vertical length, wherein the

upper leg and the lower leg are configured to be oriented to extend in a direction away from a header track in use; and

a fire-rated board member nested within a space defined by the elongate metal profile between the upper leg and the lower leg, the fire-rated board member having a second vertical length from an upper end to a lower end of the fire-rated board member, the second vertical length being less than the first vertical length;

10 wherein the upper leg comprises a first portion, a second portion positioned along a same plane as the first portion, and a downward extending protrusion connecting the first portion to the second portion.

15 17. The fire-rated component of claim 16, wherein the upper end of the fire-rated board member is positioned between the vertical leg and the downward extending protrusion of the upper leg.

18. The fire-rated component of claim 17, wherein the downward extending protrusion of the upper leg comprises 20 a V-shaped groove between the second portion and the vertical leg.

19. The fire-rated component of claim 17, wherein any 25 one or combination of the upper leg, the lower leg, and the downward extending protrusion exert a force against the board member to retain the board member nested within the elongate metal profile.
